UNITED STATES PATENT OFFICE.

ARTHUR C. WOOD, OF MANSFIELD, OHIO, ASSIGNOR TO THE OHIO BRASS COMPANY,
OF MANSFIELD, OHIO, A CORPORATION OF NEW JERSEY.

CONDUCTOR SUPPORT.

Application filed March 10, 1923. Serial No. 624,220.

To all whom it may concern:

Be it known that I, ARTHUR C. Wood, a citizen of the United States of America, residing at Mansfield, in the county of Rich-
5 land and State of Ohio, have invented cer-
tain new and useful Improvements in Con-
ductor Supports, of which the following is
a specification.

My invention relates to supporting devices
10 for conductors and has particular reference
to that class of support used to suspend a
trolley wire from a hanger or other means
of support.

One of the objects of my invention is to
15 provide a means in the support to permit of
a vertical movement of the trolley wire
adjacent the hanger and especially directly
below the hanger upon the passage of a cur-
rent collector beneath the hanger in contact
20 with the trolley wire.

Another object of my invention is to pro-
vide a resilient member against which the
current collector must act in causing the
conductor to rise vertically. My invention
25 produces a cushioned support permitting
vertical movement of the trolley wire relative
to the hanger upon the passage of a
current collector below the hanger.

Another object of my invention is to pro-
30 vide means whereby the trolley wire will
meet with yielding resistance in moving
upward adjacent the hanger which would
otherwise be the case in the construction
herein described on account of the pivotal
35 action between the members. In other words
I provide yielding means for preventing the
free pivoting of the parts constituting the
device.

One of the principal benefits derived from
40 a device embodying these objects is the
decrease in wear upon the trolley wire due
to the non-yielding character of the trolley
wire immediately below and adjacent the
hanger. Intermediate two adjacent hangers
45 the trolley wire is free to rise as the current
collector moves along in contact therewith,
but when the current collector is im-
mediately below the hanger or very close
thereto, it offers resistance to the uniform
50 freedom of the upward movement of the
trolley wire and this produces what is
termed in the trade as a "hard spot," and
has the effect of a hammer blow upon the

trolley wire. My invention is intended to
eliminate or soften the hard spots. 55

In the drawing accompanying this speci-
fication:

Fig. 1 is a side view in elevation of my
invention.

Fig. 2 is a transverse sectional view taken 60
on the line 2—2 of Fig. 1.

In the preferred form of my invention
I employ a supporting member 1 provided
with an internally threaded recess 2 which
is a means of securing the supporting mem-
ber to a hanger. A tongue 3 forms the lower
part of the supporting member 1 and has
therein a transverse opening 4 to receive
the pin 5. The pin is shown with a head
6 at one end and a cotter pin 7 at the other
70 end. Secured to the supporting member by
means of the pin 5 is a securing member 8
provided with a U shaped longitudinal
channel 9 to receive a trolley wire. In order
to attach the securing member to the trolley
75 wire positioned in the groove 9, the lips
10 are peened around the wire in the usual
way well known to those versed in the art.

Intermediate the ends of the securing
member are the ears 11 and having formed
80 therebetween the recess 13 in which is posi-
tioned the supporting member 1. The ears
11 are each provided with an elongated hole
12 having the greatest diameter in a ver-
tical direction or along the vertical axis as
85 shown. The supporting and securing mem-
bers are held together by means of the pin
5 which permits the members to pivot about
the pin 5 relative to each other, and also
permits the securing member 8 to move
90 vertically relative to the supporting mem-
ber 1. For structural reasons the washer 17
is interposed between one of the ears 11 and
the cotter pin 7.

Intermediate the ends of the supporting
member 1 is a longitudinal passage 14
95 within which is positioned a resilient mem-
ber 15 and secured therein by means of the
screw 16. The ends of the resilient mem-
ber 15 bear upon the ends of the securing
100 member and offer a yielding resistance to
the pivotal action and the vertical movement
of the securing member 8 relative to the sup-
porting member 1.

It will be evident that in operation the
105 structure described above embodying my

invention offers a resilient support for the trolley wire, and it will also be evident to those skilled in the art that many modifications may be made which will also embody 5 my invention.

I claim:

1. A conductor support comprising a support member provided with means to engage a hanger, a conductor-engaging member pivotally secured to the support member and having means to engage the conductor and resilient means secured to the support member and engaging the conductor-engaging member to yieldingly 10 maintain it in a predetermined position.
2. A conductor support comprising a supporting member provided with means to engage a hanger, a conductor-engaging member secured to the supporting member and 15 having means to engage the conductor, means permitting the said members to move relative to each other in a direction corresponding to the axis of the supporting member and resilient means secured to the supporting member and engaging the conductor-engaging member to yieldingly resist 20 said relative movement.
3. A conductor support comprising a sup- 25

porting member provided with means to engage a hanger, a conductor-engaging member pivotally secured to the supporting member and having means to engage the conductor, means permitting the said members to move relative to each other in a direction corresponding to the axis of the supporting member, and resilient means secured to the supporting member and engaging the conductor-engaging member to resist said relative movement and pivotal movement. 30

4. A conductor support comprising a supporting member provided with means to engage a hanger, a passage through the supporting member to receive a supporting pin, a conductor-engaging member provided with ears, an elongated slot in each ear, a pin passing through the passage in the supporting member and the elongated slots in the conductor-engaging member and secured therein to maintain the supporting member and conductor-engaging member in 40 operative relation and resilient means interposed between the said members to resist 45 relative movement thereof.

In testimony whereof I affix my signature.

ARTHUR C. WOOD.
